UNITED STATES PATENT OFFICE.

SAMUEL CIEGLER, OF SAN FRANCISCO, CALIFORNIA.

COMBINED SUSPENDERS, SHOULDER-BRACE, AND BELT.

SPECIFICATION forming part of Letters Patent No. 681,618, dated August 27, 1901.

Application filed May 29, 1901. Serial No. 62,417. (No model.)

To all whom it may concern:

Be it known that I, SAMUEL CIEGLER, a citizen of the United States, residing at San Francisco, in the county of San Francisco and 5 State of California, have invented certain new and useful Improvements in a Combined Suspenders, Shoulder-Brace, and Belt, of which the following is a specification.

My invention relates to an improved combined suspenders, shoulder-brace, and belt, the object of my invention being to provide a device of this character which shall be simple and durable in construction and which will not only serve as suspenders for supporting garments, but will also assist in maintaining an erect position and securing a good figure to the wearer.

My invention resides, therefore, in the novel construction and arrangement of parts for 20 the above ends, hereinafter fully specified, and particularly pointed out in the claims.

In the accompanying drawings, Figure 1 is a rear perspective view of my improved device. Fig. 2 is an enlarged front view of the 25 rear portion of the device broken away, and Fig. 3 is a broken detail view showing a modification.

Referring to the drawings, 1 represents a back piece, preferably made of leather and 30 formed with two tongues 2, having buttonholes 3 for attachment to the rear buttons of the waistband of the trousers or other nether garment. To the upper portion of said back piece are attached the ends of two straps 4, 35 said ends being inserted between said back piece and a facing 5 and firmly stitched therebetween, as shown at 6. Said straps 4 extend over the shoulders, then in front of the same, and then back underneath the arm-pits and are passed through slits 8, cut longitudinally in the back piece, one over the other, in opposite directions. The ends of the two straps are provided with buckle-fas- 40 tenings 9. Thus said straps can encircle the waist of the wearer and form a belt around the same at the same time that the upper por- 45 tions of the straps are passed around the shoulders and serve to draw the shoulders back and maintain an erect position in the wearer. From said upper portions also ex- 50 tend suspenders 11, provided with any com- mon form of suspender-ends 12 for attach-

ment to the front buttons of the waistband. Said suspenders coöperate with the remainder of the device to form a shoulder-brace for 55 said suspenders, and being attached to the front buttons of the waistband assist in preventing the straps around the shoulders slipping down and sidewise from said shoulders.

When the device is used for ladies' garments, the front suspenders 11 may be omitted. The skirt or other garment will then be suspended from the tongues 2 at the rear. The attachment of said tongues to the skirt will also assist the device in its use as a shoul- 65 der-brace, preventing the back piece from unduly working up between the shoulders.

An important feature of my invention consists in the construction of the back piece 1, having the tongues 2, formed integral therewith, and having also the slits 8, cut in said back piece for the straps 4, passed there-through. This construction is of extreme durability, as it avoids the possibility of any 70 seams in the back piece being cut through by 75 the movement of the straps through said back piece.

In the modification shown in Fig. 3 the tongues 2 are provided instead of with buttonholes with buttons 13, adjustable in position. Said buttons are used by ladies to attach the device to buttonholes in the waistband of a skirt.

In order that the stops 4 shall form shoulder-braces, it is necessary that their lower 85 ends be secured against forward movement. This I preferably do by securing the ends together; but the same result may be accomplished in other ways, as by fastening said lower ends to the back piece, without depart- 90 ing from the spirit of my invention.

I claim—

1. In a combined suspenders, shoulder-brace, and belt, the combination of a back piece having integral therewith tongues pro- 95 vided with means for attachment to the rear of the waistband, and straps fixedly attached to the upper end of said back piece, said back piece having longitudinal slits, and the straps being passed through said slits and 100 slidably therein and their ends being provided with means for fastening the ends together, substantially as described.

2. In a combined suspenders, shoulder-

brace, and belt, the combination of a back piece having tongues provided with means for attachment to the rear of the waistband, straps fixedly attached to the upper end of 5 said back piece, said back piece having longitudinal slits, and the straps being passed through said slits and slidable therein and their ends being provided with means for fastening the ends together, and suspenders 10 attached to said straps in front of the shoulder and provided with suspender-ends, substantially as described.

3. In a combined suspenders, shoulder-brace, and belt, the combination of a back 15 piece having tongues provided with means for attachment to the rear of the waistband, straps fixedly attached to the upper end of said back piece, said back piece having a guide and the straps being passed through 20 said guide and slidable therein and their ends being provided with means for fastening the ends together, and suspenders attached to said straps in front of the shoulder and provided with suspender-ends, substantially as 25 described.

4. In a combined suspenders, shoulder-brace, and belt, the combination of a back piece having tongues provided with means

for attachment to the rear of the waistband, and straps fixedly attached to the upper end 30 of said back piece, said back piece having a guide and the straps being passed through said guide and slidable therein and their ends being provided with means for fastening the ends together, substantially as described. 35

5. In a device of the character described, the combination of a back piece having tongues provided with means for attachment to the rear of the waistband, straps fixedly attached to the upper end of said back piece, and extending therefrom around the front of the shoulders and under the arms to said back piece and passed through a guide in said back piece and slidable therein, and means for securing the ends of said straps against 45 forward movement, whereby said straps then form a shoulder-brace, substantially as described. 40

In witness whereof I have hereunto set my hand in the presence of two subscribing witnesses. 50

SAMUEL CIEGLER.
